UNITED STATES PATENT OFFICE.

CHRISTOPHER C. HUDSON, OF NICEVILLE, FLORIDA.

INSULATOR.

1,233,475.

Specification of Letters Patent. Patented July 17, 1917.

Application filed October 21, 1916. Serial No. 126,950.

To all whom it may concern:

Be it known that I, CHRISTOPHER C. HUDSON, a citizen of the United States, residing at Niceville, in the county of Okaloosa and State of Florida, have invented certain new and useful Improvements in Insulators, of which the following is a specification, reference being had to the accompanying drawings.

10 This invention relates to certain improvements in insulators and it is an object of the invention to provide a novel and improved device wherein retaining fingers for a conductor are employed and wherein 15 means is employed for normally closing the space between the fingers.

It is also an object of the invention to provide a novel and improved insulator of this general character whereby a conductor or 20 wire may be applied thereto without the necessity of climbing and whereby a conductor may be readily and conveniently tightened when the requirements of practice so desire.

25 The invention also has for an object to provide a novel and improved insulator wherein an insulating body is employed which may be applied to or removed from operative position with convenience and 30 facility.

The invention consists in the details of construction and in the combination and arrangement of the several parts of my improved insulator whereby certain important 35 advantages are attained and the device is rendered simpler, less expensive and otherwise more convenient and advantageous for use, all as will be hereinafter more fully set forth.

40 The novel features of the invention will hereinafter be definitely claimed.

In order that my invention may be the better understood, I will now proceed to describe the same with reference to the accompanying drawings, wherein

Figure 1 is a view in side elevation of an insulator constructed in accordance with an embodiment of my invention;

Fig. 2 is a sectional view taken substantially on the line 2—2 of Fig. 1; and

Fig. 3 is a fragmentary view in elevation illustrating an insulator constructed in accordance with a further embodiment of my invention.

55 As disclosed in the accompanying drawings, 1 denotes a shank of predetermined

dimensions and which is adapted to be secured to a suitable support and which is provided adjacent one end with laterally directed and longitudinally spaced retaining 60 arms or fingers 2 curved inwardly one toward the other on the same radius about a common center, said arms 2 being circular in cross section and tapering outwardly.

The outer ends of said arms or fingers 2 65 are spaced one from the other a predetermined distance and secured to said outer ends are the flat springs 3 disposed inwardly on converging planes and which have their free extremities normally in contact one 70 with the other in order to close the space between the outer ends of the arms or fingers 2.

It will be noted that the springs 3 afford a substantially V-shaped pocket into which the conductor is received in order to apply 75 the same to the insulator as it is to be noted that the springs 3 will readily separate to permit the passage of a conductor or wire therebetween but will effectively serve to hold the wire against displacement. By this 80 arrangement it will be at once self-evident that the wire may be applied to the insulator without the necessity of climbing as the same may be readily passed between the arms or fingers 2 without the necessity of 85 the linemen climbing up to the insulator.

The fingers or arms 2 may be formed of any desired material but it is preferred that the same be formed of metal and that a non-conductive block 4, preferably of glass, be 90 employed therewith. As herein disclosed, the non-conductive block 4 is arcuate in form and of the same radius as each of the arms or fingers 2 and is provided in its outer face with the groove 5 to receive a 95 finger or arm 2 whereby it will be perceived that the block 4 may be readily applied to the insulator and caused to be seated intermediate the arms or fingers 2. It will be observed that in order to apply the block 100 4, one of the springs 3 must be removed which is also necessary when it is desired to remove the block.

The inner face of the block 4 midway its length is provided with the conductor or 105 wire receiving recess 6 into which the conductor or wire is adapted to be received, and whereby the same is normally held against movement relative to the arms or fingers 2.

In Fig. 3, I have illustrated an insulator 110 substantially identical to the insulator which has been previously described except that

the shank 1^a has the arms or fingers 2^a formed at an end thereof and disposed in the same general direction, this latter form of invention being especially adapted for use 5 in connection with the cross arms generally employed upon poles.

From the foregoing description, it is thought to be obvious that an insulator constructed in accordance with my invention 10 is of an extremely simple and comparatively inexpensive nature and is particularly well adapted for use by reason of the convenience and facility with which it may be assembled, and it will also be obvious that my invention 15 is susceptible of some change and modification without material departure from the principles and spirit thereof and for this reason I do not wish to be understood as limiting myself to the precise arrangement 20 and formation of the several parts herein shown in carrying out my invention in practice, except as hereinafter claimed.

I claim:

1. An insulator of the character described 25 comprising a shank provided with spaced

arms disposed on a curvature one toward the other and about a common center, the ends of said arms being spaced, means for normally closing the space between the outer ends of said arms, and a non-conductive 30 block slidably engaged with the insulator and positioned between the arms.

2. An insulator of the character described comprising a shank provided with spaced arms disposed on a curvature one toward the other and about a common center, the ends of said arms being spaced, means for normally closing the space between the outer ends of said arms, and a non-conductive 35 block slidably engaged with the insulator 40 and positioned between the arms, said block being provided with a conductor receiving recess.

In testimony whereof I hereunto affix my signature in the presence of two witnesses. 45

CHRISTOPHER C. HUDSON.
